HANDLE FOR SPOONS, FORKS, &c.

No. 19,203.

Patented July 9, 1889.

UNITED STATES PATENT OFFICE.

FREDERICK SCHMIDT, OF NORTH ATTLEBOROUGH, MASSACHUSETTS,
ASSIGNOR TO F. M. WHITNEY & CO., OF SAME PLACE.

DESIGN FOR A HANDLE FOR SPOONS, FORKS, &c.

SPECIFICATION forming part of Design No. 19,203, dated July 9, 1889.

Application filed June 13, 1889. Serial No. 314,145. Term of patent 3½ years.

To all whom it may concern:

Be it known that I, FREDERICK SCHMIDT, a citizen of the United States, residing at North Attleborough, in the county of Bristol and State of Massachusetts, have invented and produced a new and original Design for Spoons, Forks, and the Like, the same being illustrated in the accompanying photograph.

In this photograph my design is represented as applied to a spoon; but it will be understood that it may be applied to a fork and any articles of like nature with a similar handle to which the design may be applied.

The leading feature of my design consists in a series of stems curved in the direction of their length and conforming generally to the curve of the handle, the end of the spoon containing a scroll in the shape of a conventional cluster. These stems run approximately parallel to each other throughout their center

portion, while at their lower ends they have a more decided curve and partially overlap adjoining stems. The upper ends of the stems on one side and the central stem terminate in a conventional spray, while the ends of the stems on the other side are simply enlarged. The scroll around the end of the spoon has its leaves or sprays extending inwardly, filling the space between the end of the spoon and the upper ends of the stems. 25 30

What I claim is—

The described design, consisting of the curved stems and end scroll, as shown.

In testimony whereof I have signed my name to this specification in the presence of two 35 subscribing witnesses.

FREDERICK SCHMIDT.

Correction in Design Letters Patent No. 19,203.

It is hereby certified that the name of the assignee in Design Letters Patent No. 19,203, granted July 9, 1889, upon the application of Frederick Schmidt of North Attleborough, Massachusetts, for a Design for "A Handle for Spoons, Forks, &c.," was erroneously written and printed "F. M. Whitney & Co.;" that said name should have been written and printed *F. M. Whiting & Co.*, and that the said Letters Patent should be read with this correction therein that the same may conform to the record of the case in the Patent Office.

Signed, countersigned, and sealed this 30th day of July, A. D. 1889.
